FIG. 2.

FIG. 5.

FIG. 3.

FIG. 4.

Clifford M. Watrous,

BY

John Barber
ATTORNEY

UNITED STATES PATENT OFFICE.

CLIFFORD M. WATROUS, OF EAST HAMPTON, CONNECTICUT, ASSIGNOR TO GONG BELL MANUFACTURING COMPANY, OF EAST HAMPTON, CONNECTICUT, A CORPORATION OF CONNECTICUT.

TOY TELEPHONE.

Application filed June 8, 1922. Serial No. 566,904.

To all whom it may concern:

Be it known that I, CLIFFORD M. WATROUS, a citizen of the United States, and a resident of East Hampton, in the county of Middlesex and State of Connecticut, have invented certain new and useful Improvements in Toy Telephones, of which the following is a full, clear, and exact description, whereby anyone skilled in the art 10 may make and use the same.

The invention relates to a toy of the bell ringing type and particularly to a toy telephone.

The device, as illustrated, has all of the 15 general elements of the standard "desk set" type of telephone and is so arranged as to its parts that a movement of the receiver hook and its lever gives a distinct signal in simulation of the "ring" of a telephone. 20 The principal object of the present invention is to provide a duplex gong arrangement which gongs may be of different tones. A further object is to provide an extremely economical construction of a very desirable 25 character which will stand the wear and tear of play.

In a co-pending application, Serial No. 476,641, filed June 11th, 1921, which has since matured into Patent No. 1,419,902, 30 dated June 13, 1922, there is illustrated a telephone toy in which a somewhat complicated bell striking mechanism is utilized with a single gong. This type of device, having a loud ringing signal is somewhat 35 discomforting where children play with it continuously.

It is one of the purposes of the present invention to modify this loud ringing by utilizing a pair of gongs of different tones, 40 and alternately striking these gongs so that there will be a half tone effect of the signal, although the same is rapidly sounded by the striker.

This utilization of two gongs makes it 45 possible to utilize a very simple and efficient actuating mechanism for the striker to give the desired signal. Obviously, this is important in toy manufacture as it places the product in the class of comparatively cheap manufacturing costs and thus makes it 50 valuable as a toy.

Referring to the drawings:

Figure 1, is a view in front elevation of the telephone set.

Figure 2, is a view in side elevation taken 55 from the left of Figure 1.

Figure 3, is a fragmentary vertical section through the standard.

Figure 4, is a cross-sectional view through the standard. 60

Figure 5, is a fragmentary view showing a slight modification.

It is all important, in producing a popular toy, to simulate the construction and appearance of a standard article. This is 65 particularly true in the case of a toy telephone.

The child is accustomed to seeing elders use the telephone and curiosity is aroused. By providing a child with a toy instrument, 70 which has all of the general characteristics of the standard telephone, there is an incentive to use the toy, as a child has become accustomed to hear elders use the regulation phone. This not only furnishes a great 75 source of amusement but has educational value, as, of course, the child endeavors to use the toy as he has seen his elders utilize the standard telephone.

Inasmuch as it has a distinct ringing 80 signal which closely imitates the ringing of the standard telephone, interest in the toy is very much enhanced.

The toy telephone hereinafter described may be manufactured almost entirely from 85 stamped or pressed up sheet metal which may be given a high finish and attractive appearance. At the same time, it makes cheap production possible.

Referring to the drawings, numeral 1, 90 denotes the base pressed up from sheet metal and preferably covered at its lower edge with a pad 2, which serves to cover any rough edges of the base and prevents scratching and marring of highly polished 95 furniture to say nothing of the protection to the child.

Suitably secured to the base, there is a hollow standard 2', which may be made in two sections, one of the sections having 100 turned out ears 3, 4, to serve as a support for the gongs 5, 6, of course, the standard

may be of tubular form with the necessary supports for the gongs brazed or soldered thereto or any desired form of bracket may be employed and suitably secured to the 5 standard. The particular form shown is of an economical type.

Surmounting the standard 2, is a cap 3', having an extended lug 4', forming a pivotal point at 5', for the transmitter 6', and 10 mouthpiece 7, the latter are secured to a bar 8, pivoted as at 5'. There is the usual receiver hook 9, and lever 10, pivoted as at 11, said receiver hook 9, supporting the receiver 12. In simulation of the standard 15 type of telephone set, there is cord 13, extending from the receiver into the base 1.

The actuating mechanism for the striker 14, is extremely simple and, as illustrated, comprises an elongated head 15, having an 20 irregular slot 16, the angular portions of which extend to opposite sides of an arc described from the pivot point 11, of the receiver hook lever.

The striker or hammer 14, extends through 25 a slot 17, in position to strike and vibrate the gongs 5, 6, as the stem 18 of the hammer or striker is oscillated by the slotted opening 16.

The stem 18, is loosely mounted in the 30 opposite side of the standard 2, from the slot 17, having, what is substantially a ball and socket connection with the standard. A spring 19, secured at one end of the elongated head 15, of the receiver hook lever 35 and at its opposite end at the base 2, provides means for always holding the receiver hook lever at one limit of its play.

The operation of the device will be at 40 once apparent. A downward pull on the receiver hook and its lever causes the upward movement of the slotted head 15, which oscillates or vibrates the hammer 14, to alternately strike the gongs 5, 6. Upon release of the receiver hook and lever, the 45 spring 19, sharply pulls the lever back to normal position causing a further vibration of the hammer 14. It will be apparent that there are two distinct periods of vibration of the gongs or chimes 5, 6, which are 50 rapidly vibrated by the oscillatory movement of the hammer during the down stroke and return stroke of the receiver hook and its lever.

By utilizing gongs of different tones a 55 pleasant and inoffensive signal is given in a chime tone. This is particularly pleasing to the child playing with the toy and at the same time inoffensive to elders who must listen to the almost constant play of the 60 child.

In Figure 5, there is illustrated a slightly 65 modified form of mechanism for vibrating the striker or hammer 14. In this case, a serrated segment 20, upon the receiver hook 65 lever 10, serves to rapidly vibrate the ham-

mer 14, through engagement with its stem 21. This stem 21, is held in the lower portions of the serrated edge by a spring 22.

There is some economy in utilizing this form of device, both as to the amount of 70 metal employed and the stamping operations. It will be apparent that as the lever is moved, the serrated edge thereof forces the stem 21, in one direction while the spring 22, always following the stem forces 75 it in the opposite direction after said stem has reached the high point of the serration. Of course, as in the case of the device 80 illustrated, in Figure 3, a spring not illustrated is utilized for holding the lever 10, at one limit of its play.

Obviously, the exact details of the various elements may be varied to suit the exigencies of any particular requirement of construction, but in any event, the whole 85 striking and operating mechanism is of extremely simple form although very effective. Furthermore, the manufacturing cost is extremely low as compared with the excellence and stability of the toy produced. 90 One advantageous feature resides in the fact that there is little opportunity of the child being able to pull the device apart to ascertain the character of its operating mechanism. This is all enclosed in the standard 95 which, when once closed and soldered or riveted up gives little opportunity for disturbance.

What I claim as my invention and desire 100 to secure by Letters Patent is:

1. A toy telephone comprising a base, a hollow standard rising from the base, a part 105 simulating a telephone instrument supported by the standard, a gong mounted upon the standard, a lever having an end extending within the standard, a hammer for striking the gong, the stem of which is within the standard, and means carried by the lever and located within the standard for acting on the stem of the hammer to vibrate the 110 same.

2. In a toy telephone, a base, a hollow standard rising therefrom, parts simulating transmitting and receiving telephone instruments, a lever constructed to support the receiver and having one end extending within the standard, a pair of gongs operatively mounted with reference to the standard, a hammer between the gongs, and means carried by the lever that supports the receiver and located within the standard for vibrating the hammer to alternately strike the 115 gongs.

3. In a toy telephone having a base, a hollow standard rising from the base, parts 120 simulating telephone transmitting and receiving instruments, the former carried by the standard, a pair of gongs operatively mounted on the standard and at opposite 125 sides thereof, a striker intermediate said 129

gongs having a stem extending within the standard, a pivoted receiver hook lever extending within the standard and provided with serrations in contact with the stem, said 5 serrations causing a rapid vibration of the stem and its striker upon an oscillatory movement of the receiver hook.

4. In a toy telephone having a base, a hollow standard rising from the base, parts 10 simulating telephone transmitting and receiving instruments, the former carried by the standard, ears extending from the standard, gongs secured to said ears at opposite sides of the standard, a transmitter hook and lever, the latter extending within the standard, serrations appurtenant to the inner end 15 of the lever within the standard, a striker for vibrating the gongs and a stem for said striker engaging the serrations of the lever.

20 5. A toy telephone having a base, a standard rising therefrom, parts simulating the transmitter and the receiver of a telephone,

the former supported by the standard, ears extending from the standard, gongs secured to the ears at opposite sides of the standard, 25 a hammer for striking the gongs located between the two, and a lever pivotally supported by one of the said ears and having its inner end expanded and formed with serrations arranged to engage with the striking 30 hammer to vibrate it, the outer end of the lever being adapted to serve as a support for the receiver.

6. An actuating mechanism for the gongs of a toy telephone comprising gongs, a pivoted lever having a serrated end, said serrations formed as to their high and low points 35 on arcs concentric with the pivotal point of the lever, a striker for the gongs having a hammer located between them and a stem engaged directly by the serrations of the lever and a spring for normally holding said lever to one limit of its play.

CLIFFORD M. WATROUS.
